UNITED STATES PATENT OFFICE.

JAMES C. BENNETT, OF DETROIT, MICHIGAN.

BLOWER FOR BOILERS.

Application filed August 13, 1926. Serial No. 128,926.

This invention relates to blowers for boilers and has special reference to that class of steam blowers adapted to be mounted in a wall or other support, adjacent the boiler tubes, and rotated or oscillated to discharge jets of steam against the boiler tubes for soot removing purposes. Having obtained numerous patents on blowers I am aware of valves having been used adjacent the outer ends of blower arms for controlling the admission of steam to the arms. Valve opening and closing means of various types have been used in connection with the controlling valves and my invention aims to simplify this type of blower so that parts may be manufactured at a low cost and readily assembled, the blower easily and quickly installed, and its operation rendered comparatively easy.

20 My invention further aims to provide a packless automatic pressure seated valve member which cooperates with an end of a blower arm in forming a controlling valve within a suitable housing adapted to receive steam to enter the blower arm when rotated. Various means may be employed for rotating the blower arm and various kinds of stops may be provided to limit the action of the blower arm.

30 My invention further aims to provide a soot blower wherein a steam balanced valve forms part of a blower arm, the body of the valve being an integral part of the arm and movable relative to a non-rotatable stationary part of the valve. The valve body is steam balanced as near as possible so as to prevent steam pressure from materially interfering with rotation of the valve body, and provision is made for rotating either 40 end of the valve body so that it is applicable to various types of boiler settings.

45 My invention will be hereinafter specifically described and then claimed, and reference will now be had to the drawing, wherein

Figure 1 is a longitudinal sectional view of the valvular part of my blower;

Fig. 2 is a cross sectional view of the same;

50 Fig. 3 is a side elevation of the blower in connection with the portion of a boiler showing the blower arm relative to boiler tubes, and

55 Fig. 4 is a longitudinal sectional view of a portion of a blower showing a modified form of housing head.

In the drawing, the reference numeral 1 denotes a boiler setting, wall or other support adjacent boiler tubes 2 adapted to have soot and other foreign matter removed therefrom by the action of steam or a cleansing agent forcibly projected against the tubes.

60 Mounted in the wall 1 is a bearing 3 and journaled in the bearing is a sectional blower arm composed of an inner nozzle section 4, 65 and intermediate bearing section 5 and a valve section 6. The sections 5 and 6 are joined by a sleeve 7 and the sections 4 and 5 are joined by a coupling 8. These connections permit of the blower arm sections being adjusted relative to one another by rotation so that said sections may be correctly positioned for a desired installation of the blower.

70 The arm section 4 has its outer end closed, 75 as at 9, and suitably supported by a bearing 10 attached to one of the tubes 2. In the arm section 4 are internal nozzles 11 by which steam is projected against the tubes 2.

75 The outer end of the bearing 3 is formed to provide a stop lug 12 and a depending support 13 for a bracket rod 14. Adjustable on this bracket is a sleeve 15 supporting a valve housing 16 having a conventional form of stuffing box 17 through which extends the valve section 6 of the blower arm.

80 Communicating with the bottom of the valve housing 16 is a steam supply pipe 18 and this pipe will cooperate with the bracket rod 14 and the journaled blower arm in supporting the housing 16 about the end of the arm section 6.

85 The arm section 6 has a closed end 19 formed with a nut portion 20 and on the end of said arm section are two spaced apart 90 collars or valve seat members 21 and 22 connected by parallel longitudinally disposed walls 23 to cooperate with the valve seat members in forming an oblong opening 24 into the arm section 6 so that steam may 95 enter this arm section and pass through the bearing section 5 to the nozzle section 4.

100 The valve seat members 21, 22 and 23 afford an annular seat for a concave valvular member 25 seated on said seat members and normally closing the opening 24. The top of the valvular member 25 is formed with pockets 26 for coiled expansion springs 27 bearing against a cover plate 28 detachably mounted on top of the housing 16. The 105 pockets 26 have lateral wings 29 engaging walls of the housing 16 so that the valvular 110

member 25 cannot laterally shift under the influence of arm rotation by the valve section 6. The expansive force of the springs 27 is sufficient to hold the valve member 25 firmly seated on the valve seat members 21, 22 and 23 and steam can only enter the opening 24, from the housing 16, when the arm section 6 is rotated one way or the other to place the opening 24 in communication with the valve housing.

The housing 16 is provided with a detachable end head 30 having a recess 31 providing clearance for the nut portion 20 of the arm section 6. The head 30 also has an annular channel 32 and extending into this channel is the inner end of a screw 33 mounted in the head 30 and affording a stop for a pin 34 carried by the collar 22. The pin 34 protrudes into the channel 32 and when in engagement with one side or the other of the screw 33 defines the position of the arm section 6 as being with its opening 24 closed by the valvular member 25.

For rotating the tubular and sectional blower arm and sprocket wheel 35 a chain 36 may be employed. The sprocket wheel 35 has its hub portion 37 secured on the sleeve 7 by a locked set screw 38 constituting a stop in connection with the bearing lug 12. With the sprocket wheel 35 adjustable relative to the blower arm said sprocket wheel may be set so that the blower arm may be rotated approximately three hundred and sixty degrees or simply in an arc of lesser number of degrees. This stop and lug will indicate the position of the nozzles or jets 11 of the blower arm relative to the tubes 2, while the stop screw 33 and pin 34 define the closed position of the valve. Of course if the blower arm is to be always turned almost a complete revolution, the stop screw 33 and the pin 34 may be dispensed with, because the stop 38 and the lug 12 could be depended upon to define a closed position of the valve as well as a position of the nozzles or jets 11 relative to the tubes 2. However, I prefer to equip the blower with the stop pin 34 and the screw 33 because the sprocket wheel 35 can then be set so that it will function for a partial rotation of the blower arm thus limiting oscillation so that the nozzles or jets 11 are swung in a defined arc for discharging steam in predetermined directions.

The sprocket wheel and chain are preferably used when the blower is located at a height not within easy reach, but when the blower is at an elevation that a fireman or engineer may conveniently operate the blower, I provide the housing 16 with another type of head, designated 39. This head has a stuffing box 40 for a stem 41 which is tapped or otherwise fixed to the nut portion 20 of the arm section 6, as at 42, see Fig. 4. A hand wheel 43 placed on

the stem 41 will permit of the blower arm being rotated or oscillated, and said hand wheel has been shown in dot and dash lines to indicate that it is not permanently mounted on the stem, but placed thereon for each operation.

I desire to direct attention to the steam balance feature of the arm section 6, which constitutes a valve body within the housing 16. By reference to Fig. 1 it will be noted that a space exists between the valve seat member 21 and the end of the housing. The area of this space is less than the space between the head 30 and the valve seat member 22, but the pressure of steam is almost equal at both ends of the valve body, consequently the valve will be somewhat balanced, enough to prevent any material longitudinal movement of the arm section 6 during rotation. With the valve member 25 concave to seat on the members 21 and 22 the steam pressure above the valve member will cooperate with the expansive force of the springs 27 in holding the concave valve member relative to the valve body. Furthermore, it is to be noted that by virtue of the sprocket wheel 35 or the stem 41 the valve body may be rotated from either end thereof. This provision will readily adapt the valve to various types of boiler settings.

I attach considerable importance to the simplicity of construction in connection with the valve and its housing. The housing is a casting in which the arm section 6 may be easily placed and the cover 28 and head 30 readily attached to the housing. The arm section 6 only requires the valve seat members 21, 22 and 23 to support the valvular member 25 which is easily placed in position. Since the valvular member exerts a constant pressure on the valve seat members of the arm section 6, these members will be more or less ground and maintain a non-leakable connection between the valvular member and the blower arm. There are no gears, cams or the like for operating the valve and when the blower arm is rotated or oscillated, the valve is automatically opened or closed. It will be open for any desired degree of rotation of the blower arm and closed when the blower arm is in one position, therefore the operation of the blower by a fireman or engineer is readily understood. The simplicity of construction permits of the blower being used for many boiler installations, and while in the drawings I have illustrated a preferred embodiment of my invention, it is to be understood that the structural elements are susceptible to such variations and modifications as fall within the scope of the appended claims.

What I claim is:

1. A soot blower comprising a bracket member, a steam tight housing supported by

said member and provided with an inlet, a blower arm extending into said housing and having an opening adapted to communicate therewith to receive steam from said housing, a non-rotatable valvular member in said housing supported by said blower arm and normally closing the steam receiving opening of said blower arm, means connected to said blower arm adapted for rotating said arm, and means carried by said blower arm and said housing adapted to define a position of said blower arm in which said valvular member closes said steam receiving opening.

15 2. In a soot blower for boilers, a bracket, a housing adjustable on said bracket, a rotary valve body in said housing and adapted for the discharge of steam from said housing, a steam connection for said housing, a 20 non-rotatable steam pressure valve member on said body controlling communication between said valve body and said housing, and means above said bracket to facilitate rotating the valve body.

25 3. In a soot blower, the combination of a blower having a portion forming a valve

body, collars on the ends of said body, walls connecting said collars and defining therewith an opening communicating with said body, a steam receiving housing enclosing 30 said valve body, a non-rotatable valve member in said housing seated on the collars and walls of said valve body and controlling the communication between said housing and said valve body, springs in said housing retaining 35 said valve member on said collars and walls, and means adapted for rotating said valve body.

4. A soot blower comprising a fixed steam tight housing, a bearing, a blower arm 40 journaled in said bearing and extending into said housing and having an opening adapted to communicate therewith to receive steam from said housing, a non-rotatable valvular member in said housing supported by said 45 blower arm and normally closing said opening, means for rotating said blower arm, said means including a stop element engageable with said bearing and adapted to limit rotation of said arm.

In testimony whereof I affix my signature.
JAMES C. BENNETT.
